UNITED STATES PATENT OFFICE.

FRITZ JOHNSON, OF RACINE, WISCONSIN.

FLAT-IRON.

972,452.

Specification of Letters Patent. Patented Oct. 11, 1910.

Application filed May 27, 1910. Serial No. 563,707.

To all whom it may concern:

Be it known that I, FRITZ JOHNSON, a citizen of the United States, residing at Racine, in the county of Racine and State of Wisconsin, have invented certain new and useful Improvements in Flat-Irons, of which the following is a specification, reference being had to the accompanying drawing; forming a part thereof.

10 The main objects of this invention are to provide a flat iron with means within itself for generating steam for moistening clothes or fabrics effectively and evenly as they are being pressed, and generally to improve the 15 construction and operation of irons of this class.

It consists in the construction, arrangement and combination of parts as herein-after particularly described and defined in 20 the claims.

In the accompanying drawing like characters designate the same parts in the several figures.

Figure 1 is a medial vertical longitudinal section of a flat iron embodying the invention; Fig. 2 is a vertical cross section thereof on the line 2 2, Fig. 1; and Fig. 3 is a vertical cross section of the sight-feed water supply connection of the steam generator 30 chamber on the line 3 3, Fig. 1.

Referring to the drawing illustrating the invention as embodied in its preferred form, although it is susceptible of various changes in details of construction without departing 35 from the principle and scope of the invention, the flat iron comprises generally a base section *a*, a burner section *b*, and a steam generator section *c*.

The base section *a* is formed with a steam 40 chamber *d*, a number of small perforations *e* in the bottom communicating with said chamber and an upturned marginal wall *f*.

The burner section *b* which corresponds in 45 shape with the base section and is removably fitted to the upturned wall *f* thereof, is formed with a gas passage *g* surrounding an opening in the center, jet openings *h* in the underside directed downwardly toward the top wall of the steam chamber *d* in the base 50 and an upturned marginal wall *i*.

The steam generator section *c* is formed with a chamber *j* having an outwardly and downwardly projecting flange *k* removably fitted upon the upturned wall *i* of the burner

section and with flue openings or passages *l* 55 leading upwardly through the chamber *j* over the open center of the burner section *b*.

The flange *k* is formed or provided on the upper side with tubular posts *m*, the holes of which register with screw holes in the 60 burner and base sections *b* and *a*. Upon the posts *m* is mounted a cover plate or shield *n* a short distance above the top wall of the steam generating chamber *j*. This plate or shield is formed or provided on the upper 65 side with handle arms or standards *o* between which is fastened a handle grip *p* of wood or other suitable material.

The several sections of the iron with the cover plate are detachably fastened and held 70 together by screws *q* passing loosely through said plate and the upper sections *c* and *b* and threaded in the holes in the base section *a*.

The burner is provided, preferably at the rear end of the iron, with a fuel supply connection 75 consisting of an upturned elbow-shaped pipe or fitting *r*, terminating at its upper end in a cock *s* and nipple *t* for the attachment of a rubber or flexible tube (not shown) by which it is connected with a gas 80 pipe.

Below the cock *s* the pipe *r* is provided with inlet openings *u* to supply the requisite quantity of air for mixture with the gas before it issues from the openings *h*. 85

The wall of the iron is formed below the burner adjacent to the jet openings *h* with inlet openings *v*, to supply air for the proper combustion of the mixture of gas and air as it issues from the burner openings. Inlet 90 openings *w* are also formed in the wall of the iron above the burner to afford an additional and abundant supply of air to the chamber above the burner in order to insure complete combustion and prevent smoking 95 and an unpleasant odor.

The steam generating chamber *j* is connected, preferably at the rear end of the iron, with the steam chamber *d* in the base by an enlarged upturned pipe section or 100 steam chamber *x* and a tube *y*, leading from the upper end thereof into the chamber *d*.

The tube *y* is preferably provided with a coupling *z* for disconnecting the base section *a* and steam generator section *c* when desired, for any purpose such as cleaning or repairing the iron. 105

The upturned pipe section or chamber *x*

serves not only as a reservoir for the steam generated in the chamber *j*, but also to prevent any water which may collect in said chamber from flowing into the chamber *d* 5 and out of the perforations *e*.

Water is supplied to the generator chamber *j* through a sight feed connection 2, provided with a regulating valve 3, a stop cock 4 and a nipple 5, for the attachment of a 10 rubber or flexible tube (not shown) by which it is connected with a water pipe.

In the operation of the iron, gas being supplied to the burner through the pipe connection *r*, is lighted through the opening 15 (shown in Fig. 1) in the wall *f* at the rear end of the iron, and the jets of flame being directed downwardly from the openings *h* against the top wall of the chamber *d*, soon heat the entire base to, and keep it at, the 20 desired temperature, which is regulated by means of the cock *s*. Water being admitted through the sight feed connection 2 into the chamber *j*, is converted therein into steam by the heat of the burner below, the products 25 of combustion passing upwardly through the open center of the burner and the flue openings *l* and keeping the walls of said chamber hot. The steam thus generated passes into and fills the enlarged upwardly extending pipe section or chamber *x* from the upper part of which it passes through the tube *y* into the chamber *d*, where it is further heated and dried, issuing therefrom through the perforations *e* in the bottom of the iron 30 and evenly and effectively moistening the garment, or fabric, as the iron passes over and presses it. The supply of water to the generator chamber *j* may be observed by the operator as it passes through the sight feed 35 connection 2 and is regulated by the adjustment of the valve 3.

By the construction and arrangement of the parts of the iron as shown and described, the heat produced by the burner is most effectively and economically applied to keep 40 the base hot and at the same time to generate steam for moistening garments or fabrics as they are pressed. The separation of the parts of the iron and access to the interior for cleaning and repairing the same 45 are also facilitated.

I claim:

1. In a flat iron the combination of a 50 chambered and perforated base, a steam generating chamber located above the chambered base and connected therewith by a steam conduit, and a burner interposed between said base and steam generating chamber and adapted to heat the same.

2. In a flat iron the combination of a base 55 having a steam chamber and perforated bottom, a steam generating chamber located above the base and connected with the chamber therein by a steam conduit having an upturned bend extending above the steam

generating chamber, and a burner interposed between the base and steam generating chamber and adapted to heat both.

3. In a flat iron the combination of a base having a steam chamber and perforated bottom, a steam generating chamber located above and connected by a steam conduit with the chamber in the base and having a sight feed water supply connection provided with a regulating valve, and a burner interposed between the base and steam generating chamber and adapted to heat both. 70 75

4. In a flat iron the combination of a base having a steam chamber and perforations in the bottom communicating with said chamber, a chambered burner open in the center and having jet openings directed downwardly toward the base, and a steam generating chamber located above the burner and having a water supply connection and a steam connection with the chamber in the base. 80 85

5. In a flat iron the combination with a chambered base having perforations in the bottom, an open center gas burner having a fuel supply connection and jet openings directed downwardly toward the base, and a steam generating chamber located above said burner and having flue passages, a water supply connection and a steam connection with the chamber in the base. 90 95

6. In a flat iron the combination of a base section having a chambered and perforated bottom, an open center burner section mounted upon said base section and having a fuel supply connection and downwardly directed jet openings on each side of the central opening therein, a chambered steam generating section mounted upon said burner section over the central opening 100 therein and having a water supply connection and a steam connection with the chamber in the base, a cover plate provided with a handle, and means for detachably securing the said sections and the cover plate 105 together. 110

7. In a flat iron the combination of a chambered base section having a perforated bottom and an upturned marginal wall with air inlet openings, an open center chambered burner section removably fitted to the upturned wall on the base section and having a fuel supply connection and an upturned marginal wall, a chambered steam generator section having a steam connection with the chambered base and an upturned marginal flange removably fitted to the upturned wall of the burner section, and screws detachably securing the several sections together. 115 120

8. In a flat iron the combination of a chambered base having a perforated bottom, an open center burner having a fuel supply connection and jet openings in the under side directed downwardly toward the top 125 130

wall of the chambered base, a steam generating chamber connected by a steam conduit with the chamber in the base, and having flue openings leading upwardly through it above the open center of the burner, a wall inclosing a space above the burner and a wall having air inlet openings and inclosing a space below the burner.

9. In a flat iron the combination of a chambered base having a perforated bottom, an open center burner having a fuel supply connection and jet openings in the under side, a steam generating chamber connected

by a steam conduit with the chamber in the base and having flue openings leading upwardly through it above the open center of the burner, and walls inclosing spaces above and below the burner and having air inlet openings communicating with said spaces.

In witness whereof I hereto affix my signature in presence of two witnesses.

FRITZ JOHNSON.
